UNITED STATES PATENT OFFICE.

ROBERT C. LAFFERTY, OF NEW YORK, N. Y.

DESIGN FOR AN ARTICLE OF MANUFACTURE.

54,323.

Specification for Design.

Patented Dec. 23, 1919.

Application filed July 24, 1918. Serial No. 246,602. Term of patent 3½ years.

To all whom it may concern:

Be it known that I, ROBERT C. LAFFERTY, a citizen of the United States, residing at 3135 Broadway, in the borough of Manhattan, city, county, and State of New York, have invented a new, original, and ornamental Design for an Article of Manufacture, of which the following is a specifica-

tion, reference being had to the accompanying drawing, forming a part hereof.

The figure is a view of an emblem.

I claim:

The ornamental design for an article of manufacture, as shown.

ROBERT C. LAFFERTY.
